UNITED STATES PATENT OFFICE.

JAMES SHIREY, OF CHICAGO, ILLINOIS.

LOCKING MEANS FOR DOORS.

1,176,407.

Specification of Letters Patent. Patented Mar. 21, 1916.

Application filed August 28, 1914. Serial No. 859,015.

To all whom it may concern:

Be it known that I, JAMES SHIREY, a citizen of the United States, residing at Chicago, in the county of Cook and State of Illinois, have invented a new and useful Locking Means for Doors, of which the following is a specification.

My invention relates to improvements in locking-means for doors, and my object is in 10 general to provide a simple, strong and durable locking-mechanism capable of application to all common forms of doors.

Further objects and advantages of my invention will appear from the following detailed description of the same, in which, for purposes of illustration, I will particularly describe an embodiment of the invention as applied to a well-known type of double-door.

In the description, reference will be made 20 to the accompanying drawings, in which— Figure 1 is a front elevation of a double door and frame for the same, showing the locked and unlocked positions; Fig. 2 is a detailed perspective view of the slide-rod and 25 the connection with the locking-bar; Fig. 3 is an enlarged sectional view of the end of the locking-bar and the socket of the door-frame in which it engages; Fig. 4 is a section on line 4 of Fig. 3; Fig. 5 is an enlarged 30 front elevation of the locking-plate which is secured to the door, the key of the locking-bar being shown in section; Fig. 6 is a section on line 6 of Fig. 5, showing also the locking-bar and key; Fig. 7 is a rear face 35 view of the locking-plate; Fig. 8 is a section on the line 8 of Fig. 6, and Fig. 9 is a detail section on the line 9 of Fig. 1.

In the drawings, 10 indicates the door-frame in which is mounted a pair of swing-doors 11, 12. These doors may be of either of the one-way or two-way type, the locking-means being adapted for both constructions, as will later appear. To apply my lock to such a door and frame, I mount 45 upon the inner face of one of the vertical frame-members a slide-bar 13 which is spaced away from the door-frame, as by the angular feet 14. Mounted to slide on the bar 13 is a sleeve 15 which has formed thereon the 50 tongue 16 to which is pivoted, as by a pin or rivet 17, the slotted-end plug 18. The outer end of the plug is reduced as at 19 to fit within the bore of a tubular locking-bar 20,

a bolt or other fastening means, indicated at 21, being employed to hold the plug within 55 the bore of the tube. Intermediate the length of the locking-bar it is encircled by split sleeves 22 carrying key-members 23 which are adapted to engage within the key-hole-shaped apertures of locking-plates 24. The 60 split sleeves 22 are clamped in proper position upon the locking-bar by cap-screws 25.

Referring to Figs. 5 to 8, it will be seen that the locking-plates 24 are let into the face of the door, as indicated at 26, so as to 65 lie flush with the same, and are secured in position, as by counter-sunk screws 27. Back of the plates the doors are cut away to form rectangular recesses 28 which accommodate the enlarged ends 29 of the keys. 70 The apertures 30 of the locking-plates are of key-hole shape, as stated, so that the enlarged ends of the keys may be introduced into the upper enlargement of the apertures 30, and upon being moved downwardly are 75 locked within the recess 28 by the side walls 31 of the lower narrowed ends of the apertures 30. As shown in Fig. 8, these side-walls flare inwardly to engage correspondingly flared surfaces 32 on the enlargements 80 29 of the keys. As a means of drawing the sleeves 22 tightly into engagement with the outer faces of the locking-plates, I form upon the inner faces of the locking-plates the inclined surfaces indicated at 33 in Fig. 85 6. These surfaces coact with the enlarged heads 29 of the keys, to wedge the same tightly in place as the keys are forced downwardly in the slots.

Referring to Figs. 3 and 4, it will be seen 90 that the free end of the locking-bar is slotted at 33^a to receive a hasp 34 which is threaded into the telescoping tube-section 35. A second hasp, shown at 36, is threaded into the wall of the locking-bar so as to lie adjacent 95 to and in alignment with the hasp 34 when the telescoping-section 35 is in its extended position. To lock the hasps in the position shown in Fig. 3, a padlock, conventionally illustrated at 37, may be employed. The 100 telescoping-section 35 engages within a socket 38 let into the inner face of the vertical side-frame member of the door-frame. This socket, like the locking-plate, is preferably flush with the surface in order to present a neat appearance. A socket 39, similar 105

to the socket 38, may be let into the under face of the top-frame member of the door-frame.

The operation of my locking-mechanism is as follows: When the parts are in the unlocked or inoperative position, as indicated in dotted lines in Fig. 1, the telescoping-section 35 will be engaged with the socket 39, (being so held by the padlock 37, not shown in this figure) the sleeve 15 will be at the bottom of the slide-bar 13, and in this position of the parts the doors will be entirely unobstructed and free to swing in either direction. When it is desired to lock the doors, the padlock 37 will be removed and the hasp 34 will be thrown downwardly in the slot 33, thus causing the telescoping-section 35 to slide within the tubular locking-bar until it gets free of the socket 39. The end of the bar may then be swung downwardly about the pivot 17, and at the same time the sleeve 15 will be raised on the slide-bar 13 to bring the locking-bar into approximately horizontal position opposite the locking-plates of the doors, the keys 23 being opposite the enlarged upper ends of the apertures in the locking-plates. The free end of the locking-bar which formerly stood at a slight angle to the doors will now be moved back toward the same, causing the keys 23 to pass through the apertures in the locking-plates, and when this has been effected, the free end of the bar will be swung downwardly, thus causing the keys to move downwardly and become wedged within the lower slots of the locking-plates. If the parts have been accurately fitted, the end of the locking-bar will now stand opposite the socket 38, and the hasp 34 may be pushed forward to engage the telescoping-section 35 within the socket. The padlock 37 may then be snapped through the hasps 34, 36. It will be seen that in this position of the parts the doors are positively held against all movement. If they are folding-doors, as described, they can not be swung in either direction, the keys 23 being wedged so tightly within the apertures of the locking-plates as to even prevent rattling of the doors. As an additional means of preventing rattling of the doors, I may fasten to the faces of the same the wedge plates 40, shown in Figs. 1 and 9. These plates have inclined front faces which in the locked position of the parts bear against and tightly wedge the locking-bar 20. These plates 40 are not at all necessary to the action of the locking means, however, and need only be used where it is important to prevent the least rattling of the parts.

It will be readily understood that the form of locking-means which I have described as applied to a double swinging-door will serve without change for a single door of the swinging type or for a single or double door

of the sliding type, the form of the locking arrangement being such that the door or doors are positively held against all movement. The same form of locking device may be applied in precisely the same way to revolving-doors, it being understood that the sections of revolving-doors are pivoted to one another so that they may be brought into a single plane when it is desired to lock the door. In such position of the parts, the door-sections would occupy the same relation to one another as do the double folding-doors 11 and 12 in Fig. 1; and the locking-bar would be applied in precisely the same way, excepting that it would be necessary, of course, to recess the door-frame or casing to receive the slide-bar 16 and also to receive the locking-bar when it is in the inoperative position.

In order to adapt my locking mechanism for doors of different sizes, it is only necessary to change the length of the locking-bar and the slide-bar, and this may be done by any dealer in such apparatus. The locking-plates and all other fittings are identically the same for all classes and sizes of doors to which the locking-mechanism may be applied.

While I have shown and described in considerable detail a construction embodying my invention, it is to be understood that such description and showing is illustrative only, and that my invention is not to be construed as limited to the structural features or combinations of elements shown, except in so far as such limitation is included within the appended claims.

What I claim as new and desire to secure by Letters Patent is—

1. A locking means for doors, comprising a locking-bar, means for locking said bar to a door-frame in a position to extend from side to side of the latter, a key-member on said bar, and an apertured locking-plate adapted to be secured to a door, the aperture of said plate being of such form as to freely receive the key-member in one position of the parts and to lock the same in another position of the parts.

2. A locking means for doors, comprising a locking-bar, means for locking said bar to a door-frame in a position to extend from side to side of the latter, a key-member on said bar, said key-member having an enlarged head-portion and a reduced stem-portion, and an apertured locking-plate adapted to be secured to said door, the aperture of said plate being of such form as to freely receive the enlarged head of the key-member in one position and to lock the same in another position.

3. A locking means for doors, comprising a locking-bar, means for locking said bar to a door-frame in a position to extend from side to side of the latter, a key-member on

said bar, and a locking-plate adapted to be secured to a door, the aperture of said plate being of key-hole form.

4. A locking means for doors, comprising
5 a locking-bar, means for locking said bar to a door-frame in a position to extend from side to side of the latter, a key-member on said bar, said key-member having an enlarged head-portion and a reduced stem-
10 portion, and an apertured locking-plate adapted to be secured to a door, the aperture of said plate being of key-hole form.

5. A locking means for doors, comprising
15 a locking-bar, pivoted means for securing said bar to a door-frame in a position to extend from side to side of the latter, a key-member on said bar, and an apertured locking-plate adapted to be secured to a door, the aperture of the plate being of such form
20 as to freely receive the key-member in one position of the parts and to lock the same in another position of the parts.

6. A locking means for doors, comprising a locking-bar, means for pivoting said bar to
25 a door-frame at one end, means for locking said bar to a door-frame at the other end, a key-member on said bar, and an apertured locking-plate adapted to be secured to a door, the aperture of the plate being of such
30 form as to freely receive the key-member in one position of the parts and to lock the same in another position of the parts.

7. A locking means for doors, comprising a locking-bar, a telescoping section mounted
35 on said bar, a socket-member adapted to receive the telescoping section in its extended position, a key-member on said bar, and an apertured locking-plate adapted to be secured to a door, the aperture of the plate being of such
40 form as to freely receive the key-member in one position of the parts and to lock the same in another position of the parts.

8. A locking means for doors, comprising
45 a locking-member, pivoted means for securing one end of said bar to a door-frame, a telescoping section mounted on the other end of said bar, a socket-member adapted to be secured to a door-frame and to receive said
50 telescoping section in its extended position, a key-member on said bar, and an apertured locking-plate adapted to be secured to a door, the aperture of the plate being of such
55 form as to freely receive the key-member in one position of the parts and to lock the same in another position of the parts.

9. A locking means for doors, comprising
a slide-bar adapted to be mounted on a door-frame, a sleeve slidable on said bar, a locking-bar pivoted to said sleeve, means for locking the other end of said bar to the door-frame, a key-member on said bar, and an apertured locking-plate adapted to be secured to a door, the aperture of the plate
65 being of such form as to freely receive the

key-member in one position of the parts and to lock the same in another position of the parts.

10. A locking means for doors, comprising
70 a slide-bar adapted to be secured to a door-frame, a sleeve slidable on said bar, a locking-bar pivoted to said sleeve at one end and having a telescoping-section mounted on the other end, a socket-member adapted to be secured to a door-frame and to receive the telescoping end of said bar in its extended position, a key-member on said bar, and an apertured locking-plate adapted to be secured to a door, the aperture of the plate being of such form as to freely receive
75 the key-member in one position of the parts and to lock the same in another position of the parts.

11. A locking means for doors, comprising
80 a locking-bar, a slide-bar adapted to be secured to a vertical member of a door-frame, a sleeve slidable on said bar, a locking-bar pivoted at one end of said sleeve and having a telescoping section mounted on the other end, socket-members adapted to be
85 mounted in the door-frame in position to receive the telescoping-section of the locking-bar in its extended position and to lock the bar in operative or inoperative position with respect to the doors, a key-member on
90 said locking-bar, and an apertured locking-plate adapted to be secured to a door, the aperture of the plate being of such form as to freely receive the key-member in one position of the parts and to lock the same in another position of the parts.

12. A locking means for doors, comprising
95 a locking-bar having a telescoping end-section, hasp-members secured to said bar and to said telescoping-section, means for locking said bar to a door-frame, a key-member on said bar, and an apertured locking-plate adapted to be secured to a door, the aperture of the plate being of such form as to freely receive the key-member in one
100 position of the parts and to lock the same in another position of the parts.

13. A locking means for doors, comprising
110 a locking-bar, means for locking said bar to a door-frame, a key-member on said bar, said key-member having an enlarged head-portion and a reduced stem-portion, and a locking-plate adapted to be secured to a door and having an aperture therein to receive the key-member, the walls of said
115 aperture being inclined to produce a wedging action.

14. A locking means for doors, comprising
120 a locking-bar, pivotal means for securing one end of said bar to a door-frame, a telescoping section on the opposite end of said bar, coöperating hasp-members secured to said bar and said telescoping section, a socket-member adapted to be let into a door-frame and to receive the telescoping-section
125 130

in the extended position of the same, a key-member secured to said bar, said key-member having an enlarged head-portion with flaring side-walls, and an apertured locking-
5 plate adapted to be secured to a door, the aperture of the plate being of such form as to freely receive the key-member in one position of the parts and to lock the same in an-

other position of the parts, the side walls of said aperture being of wedge-shape to co- 10 operate with the inclined walls of said key-member.

JAMES SHIREY.
